UNITED STATES PATENT OFFICE.

MICHAEL MUTRO, OF CHESTER, PENNSYLVANIA, ASSIGNOR OF TEN ONE-HUNDREDTHS
TO GEORGE BELISNANSKI, OF CHESTER, PENNSYLVANIA.

1,242,224.

Specification of Letters Patent.

Patented Oct. 9, 1917.

Application filed May 28, 1917. Serial No. 170,400. Quoted in the margin are the extracts of record in the Patent Office.

To all whom it may concern:

Be it known that I, MICHAEL MUTRO, a subject of the Emperor of Austria, residing at Chester, in the county of Delaware and State of Pennsylvania, have invented certain new and useful Improvements in Locks, of which the following is a specification:

This invention relates to locks and has special reference to that type of lock which is known as a door lock.

One important object of the invention is to improve the general construction of devices of this character.

A second important object of the invention is to provide an improved form of lock which may be locked without the use of a key so that the bolt can not be retracted by rotation of the door knob.

A third important object of the invention is the provision of an improved keyless lock of this description, wherein the same elements that are ordinarily used to effect retraction of the bolt may be used for effecting locking of both bolt and knob.

With the above and other objects in view, as will be hereinafter apparent, the invention consists in general of certain novel details of construction and combinations of parts hereinafter fully described, illustrated in the accompanying drawings, and specifically claimed.

In the accompanying drawing, like characters of reference indicate like parts in the several views; and

Figure 1 is a vertical section through the casing of a lock constructed in accordance with this invention, the inner portions of the lock being shown in elevation.

Fig. 2 is a section on the line 2-2 of Fig. 1.

Fig. 3 is a section on the line 3-3 of Fig. 2.

Fig. 4 is a detail perspective view of the improved locking bolt.

In carrying out the objects of this invention there is provided a casing having side walls 10, a front edge wall 11, a rear edge wall 12, bottom wall 13 and top wall 14. Within this casing is fixed a plate 15 having at opposite edges flanges 16 which are provided with openings 17 adapted to receive the reduced ends 18 and 19 of a locking bolt plate 20. This locking bolt plate 20 is provided on its forward end with a beveled nosed head 21 which is reciprocably

mounted in an opening 22 formed in the front wall 11. Moreover, on the plate 20 there is provided a lug 23 against which bears a spring 24 having one end fastened, as at 25, to the bottom wall 13 of the casing and having its other end passing through lugs 26 carried by the plate 15. This spring is so arranged that it presses against the lug 23 in such direction as to maintain the head 21 in projecting position.

In the plate 20 is an elongated slot 27 and through this slot and the walls 10 of the casing passes the spindle of the lock. This spindle consists of a solid inner member 28 having a head 29 fixed to one end thereof and on this solid member is mounted a sleeve 30 which is keyed to the member 28 by means of a T-shaped key 31. Fixed to the opposite end of the solid member 28 by means of a screw 32 is a head 33. The spindle is of such length that it may slide through the casing as well as rotate therein.

Fixed on the sleeve 30 is a cam plate 34 having oppositely disposed sectoral portions 35 each provided with an opening 36. Between these portions 35 is the cam portion 37 of this plate and this is also provided with an opening 38 similar to the openings 36. This cam portion 37 normally bears against a lug 39 formed on the plate 20 but, by sliding the spindle longitudinally the plate may be disengaged from this lug whereupon the spindle may be turned sufficiently to bring one of the openings 36 or the opening 38 into alignment with the lug 39 so that the lug may pass into such opening when the spindle is slid back and this will prevent rotation of the spindle and cam plate and will also prevent movement longitudinally of the bolt.

In order to maintain the cam plate in operative relation to the lug 39 there is provided a coil spring 40 which surrounds the spindle and bears at one end against one of the sides 10 of the casing while the other end bears against the cam plate 34.

In order to provide for additional locking of the door, as from the inside of a room or the like there is also used in the casing a bolt 41 reciprocably mounted in guides 42 and normally urged forward by a spring 43. This bolt is controlled by a thumb latch 44 passing through an opening 45 in the wall 14 of the casing.

In the ordinary use of the device the

spindle and other parts are in the position shown in Fig. 1. Now in this position rotation of the spindle in the proper direction will cause the cam portion 37 of the cam 5 plate to force the bolt inward so that the door may be opened. However, when it is desired to lock the door the cam plate is first rotated, until it assumes, provided it is not already in such position, the position 10 shown in Fig. 1. Then the knob 33 is pushed inward until the cam plate is free from the lug 39. The spindle is then rotated until one of the openings 37 or 38 comes into registry with the lug 39 when it is allowed, 15 under the influence of the spring 40, to move outward. Thus the lug 39 will enter the respective opening and so long as the spindle is not pushed in no rotary movement of the spindle or movement of the bolt can take 20 place. Thus in order to operate the device a person would have to be acquainted with the fact that he would first of all have to push the spindle in to free the cam plate from the lug, then rotate the spindle part 25 way until the lug could be engaged by the cam portion 37 of said plate.

There has thus been provided a simple and efficient device of the kind described and for the purpose specified.

30 It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, what is claimed as new, is:—

40 1. A lock including a casing, a spindle extending through the casing and slidably and rotatably mounted in the walls thereof,

Copies of this patent may be obtained for five cents each, by addressing the "Commissioner of Patents, Washington, D. C."

a reciprocable bolt in said casing and projectable from one edge thereof, a lug on said bolt, a spring normally holding the bolt in projected position, a cam plate fixed on said spindle and having its edge normally engaging said lug, said plate being provided with an opening to receive said lug and lock the bolt against movement, and a spring bearing against the plate and normally holding said plate in position to engage the lug.

2. A lock including a casing having an opening in one edge, a plate fixed within said casing having oppositely disposed flanges provided with openings aligned with the opening in the casing, a bolt consisting of a sheet metal plate having reduced terminal portions slidably fitted in the openings of said flanges, one of said terminal portions having a head fixed thereto and slidable in the casing, a lug at the front of said plate, a leaf spring fixed to the casing and bearing against the lug to force the bolt outward, a spindle extending through said casing and plate and slidably and rotatably mounted in the casing, a cam plate fixed to said spindle and having oppositely disposed projecting sectors each having an opening therein, a lug on the first plate against which the cam portion of the cam plate bears normally, said last lug being receivable in one of the openings of the cam plate to lock the bolt against movement and a coil spring surrounding the spindle and bearing against the cam plate to hold the latter in position to engage the last-mentioned lug.

In testimony whereof I affix my signature.
